UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MAGAZINE.

Application filed January 16, 1928. Serial No. 246,954.

This invention relates to a weft carrier magazine in an automatic weft replenishing loom, such as is shown and described in my prior application Serial No. 212,996, filed August 15, 1927. In this type of loom, the weft carriers are stored in separate compartments in a magazine, and each compartment is moved downward to present a weft carrier in transfer position upon indication of weft exhaustion.

It is the object of my invention to improve and simplify the mechanism for depressing a selected compartment to delivery position.

Another feature of my invention relates to the provision of improved means for holding a compartment elevated above normal position for refilling, at the same time rendering inoperative the mechanism for lowering the compartment to delivery position.

My invention further relates to arrangements and combinations of parts which will be hereinafter described and more particularly pointed out in the appended claims.

A preferred form of the invention is shown in the drawings in which

Fig. 1 is a left hand side elevation of parts of my improved magazine;

Fig. 2 is a partial plan view thereof;

Fig. 3 is a partial sectional front elevation of the magazine, taken substantially along the line 3—3 in Fig. 1;

Fig. 4 is a partial sectional front elevation, taken along the line 4—4 in Fig. 1;

Fig. 5 is a detail sectional plan view, taken along the line 5—5 in Fig. 4; and

Figs. 6, 7, 8, 9 and 10 are sectional elevations similar to Fig. 4 but showing the parts in different successive positions.

Referring to the drawings, I have indicated a magazine having a frame 20 adapted to be mounted in fixed position upon the loom. The magazine is provided with a series of vertical compartments 21 (Fig. 2) for the weft carriers W, said compartments having guide portions 22 (Fig. 5) slidable in vertical recesses 23 in the frame 20 and retained in vertically movable position by outer members or bars 25, each secured to its respective compartment by bolts or screws 26 (Fig. 4).

Whenever a weft carrier from a particular compartment is to be delivered, the compartment is depressed so that its lower delivery end is below the other compartments, thus permitting its lowermost weft carrier to be removed by a transfer member,

all as fully shown and described in my prior application.

My present application relates particularly to improved means for indicating and depressing a selected compartment and also for yieldingly retaining the compartment in an elevated position for refilling.

For selectively depressing the compartments, I provide each compartment with a latch 30 having a slot 31 through which extends a pivot stud 32 in the member 25. The lower end of the latch is provided with a lug or projection 33 and the upper end of the latch is engaged by a spring 34 which holds the latch yieldingly in the position shown in Fig. 4. The supporting member 25 is provided with a shoulder or projection 36 adjacent the latch 30.

An indicating member or slide 40 (Fig. 2) is mounted in supports 41 on the frame 20 and is yieldingly moved to the left in Figs. 1 and 2 by a light coil spring 42. The offset end 43 (Fig. 2) of the indicating slide 40 is positioned for engagement with a bar 44 actuated and controlled by the weft detecting mechanism of the loom, as fully set forth in my prior application.

The indicator slide 40 is provided with a cam projection 45 for each compartment and, when moved longitudinally by the bar 44, these cam projections 45 engage the several latches 30, moving them from the position shown in Fig. 6 to the position shown in Fig. 7. Such movement advances the lug or projection 33 of each latch into position for engagement by one of the actuating arms 46 on a rock shaft 47. The rock shaft is movable axially in fixed relation to the movements of the drop boxes, as is customary in such weft carrier magazines, so that only one of the latches 30 will be engaged by an actuating arm 46 at any given time. The latch thus engaged will always correspond to the compartment having weft carriers similar to the running weft carrier which is substantially exhausted.

The rock shaft 47 is provided with an arm 48 (Fig. 8) connected by a link 49 to a lever 50 pivoted at 51 and having a cam roll 52 positioned in the groove 53 of a cam 54 mounted on the usual cam or bottom shaft 55, which makes one revolution for each two picks of the loom. The cam is so shaped that the member 46 will be given alternate rocking movements, the first downward movement

being relatively short and the second downward movement being of substantially greater extent, while the upward movement of travel is the same in each case. The method of operation of the latches 30, the indicator slide 40, and the actuating members 46 will be hereinafter described.

The upright bars or members 25, movable with the compartments 21, are preferably provided with notches 56 (Fig. 1) yieldingly engaged by springs 57 or 58 which hold the compartments yieldingly in normal position. The spring 57 between two adjacent compartments may preferably be made as a double spring, while single springs 58 are provided for the outer compartments.

When a compartment is depressed for weft replenishment, its spring 57 or 58 is moved yieldingly out of the upper notch 56 and slides along the straight upper end of the corresponding bar 25. If, however, it is desired to refill a weft carrier compartment, the compartment is pulled upward manually to the position indicated in broken lines in Fig. 1, and the corresponding spring 57 or 58 engages the lower notch 56 and holds the compartment raised during replenishment. While in raised position, the compartment is removed from the path of operation of the color slide or indicator 40, as indicated in Fig. 4, so that that particular compartment will not be indicated or depressed during the refilling thereof.

The operation of the indicating and depressing mechanism is as follows: Upon indication of weft exhaustion by the detecting mechanism (not shown), the bar 44 (Fig. 2) will be moved to the dotted line position in said figure, and when swung forward in this position, it will engage the end 43 of the indicator slide 40, causing the latches 30 to be moved from the position shown in Figs. 3 and 6 to the position shown in Fig. 7, with their projections 33 extending beneath the actuating arms 46.

The shaft 47 is movable endwise in fixed relation to the movements of the drop boxes, so that one of the arms 46 will always be aligned with the latch 30 of the compartment corresponding to the running shuttle. The arms 46 then receive their short downward movement from the cam 54, as previously described, which short movement is sufficient to slide the latch 30 downward on its supporting bar 25 to the position indicated in Fig. 8, such movement being permitted by the pin and slot connection between the latch and the bar.

This movement causes the lower end of the latch to project beyond a shoulder 60 formed in a recess in the bar 25, which shoulder holds the latch outward in operative position while the arm 46 swings upward as indicated in Fig. 9. The latch 30 thus holds the indication, in case the drop boxes should be

shifted before the next downward movement of the arm 46.

Upon the next long downward movement of the arms 46, when one of them is aligned with the indicated latch 30, the latch and its supporting bar 25 will be moved downward, as indicated in Fig. 10, depressing the corresponding weft carrier compartment to position to deliver a weft carrier to the transfer mechanism, as fully described in my prior application. At the beginning of the return upward movement of the arms 46, the operative arm will first engage the latch 30 and slide it upward on its pivot stud 32 to the raised position of Fig. 3, thus clearing the abutment 60. The arm 46 will then engage the lug 36 on the corresponding slide bar or support 25 and will thus restore the parts to the normal or initial position of Fig. 6.

I have thus provided very simple mechanism for receiving an indication of weft carrier exhaustion and for preserving the indication until the return of the corresponding shuttle and weft carrier to the magazine side of the loom. I have also provided means for holding a weft carrier compartment elevated for refilling and for rendering the depressing mechanism inoperative with respect to a compartment thus elevated.

Having thus described my invention and the advantages thereof, I do not wish to be limited to the details herein disclosed otherwise than as set forth in the claims, but what I claim is:—

1. In a weft replenishing magazine, a frame, a plurality of substantially vertical weft carrier compartments each separately movable in said frame, selective means to move a compartment downward to weft carrier delivery position and means to hold a selected compartment elevated above normal position for refilling, said selective lowering means being inoperative with respect to a compartment thus elevated but being restored to operative relation to said compartment by the return of said compartment to normal position.

2. In a weft replenishing magazine, a frame, a plurality of substantially vertical weft carrier compartments each separately movable in said frame, selective means to move a compartment downward to weft carrier delivery position, said compartments being manually movable upward from normal position for refilling, and yielding means to hold each compartment in either normal or elevated position.

3. In a weft carrier magazine, a frame, a weft carrier compartment mounted for substantially vertical movement in said frame, a latch on said compartment, and an actuator having alternate short and long depressing movements, said actuator co-operating with said latch to move said compartment downward to delivery position.

4. In a weft carrier magazine, a frame, a weft carrier compartment mounted for substantially vertical movement in said frame, a latch on said compartment, an actuator having long and short depressing movements, and an indicating member effective to move said latch into position for engagement by said actuator upon indication of weft exhaustion.
10. 5. The combination in a loom as set forth in claim 4, in which the latch has a pin and slot connection to said compartment and is movable downward independently of its compartment by the short stroke of said actuator, and
15 in which means is provided to hold said latch in engaging position until again engaged by said actuator on the long depressing movement thereof.
6. In a weft carrier magazine, a vertically movable compartment, a latch having a short slot therein, a pin on said compartment extending through said slot, an actuator having a long and a short downward stroke, said actuator being effective on its short stroke to lower said latch on its support substantially 25 the length of said slot and being effective on its long stroke to lower said compartment to delivery position, and said compartment having an abutment engaged by said latch when lowered by said short stroke, whereby said latch is retained in position for engagement thereafter by said actuator on its long downward stroke.

In testimony whereof I have hereunto affixed my signature.

ALBERT A GORDON.
